DESIGN FOR A SHOE

Louis David Morrell, New York, N. Y., assignor to Kidskin Guild, New York, N. Y.

Application July 17, 1936, Serial No. 63,897

Term of patent 3½ years

To all whom it may concern:

Be it known that I, Louis David Morrell, a citizen of the United States of America, residing in city of New York, county of New York, and State of New York, have invented a new, original, and ornamental Design for a Shoe of which the following is a specification, reference being had to the accompanying drawing, forming part thereof,

Fig. 1 is a plan view of a shoe showing my new design.

Fig. 2 is a perspective view of a shoe as shown in Fig. 1.

The characteristic feature of my design resides in the flower arrangement on the front portion of the shoe.

I claim:

The ornamental design for a shoe substantially as shown and described.

LOUIS DAVID MORRELL.
